(57) **CLAIM**

The ornamental design for car wash equipment frame, as shown and described.

DESCRIPTION

FIG. 1 is a perspective view of a car wash equipment frame embodying the new design;

FIG. 2 is a front elevational view thereof;

FIG. 3 is a right side elevational view thereof, the left side elevational view being a mirror image thereof;

FIG. 4 is a top plan view thereof; and,

FIG. 5 is a bottom plan view thereof.

The broken lines in FIGS. 1-5 represent environmental structure and form no part of the claimed design.
